(57) **CLAIM**

The ornamental design for a fuse holder, as shown and described.

DESCRIPTION

FIG. 1 is a perspective view of a fuse holder according to our new and ornamental design;

FIG. 2 is a right side view thereof;

FIG. 3 is a left side view thereof;

FIG. 4 is front view thereof;

FIG. 5 is a rear view thereof;

FIG. 6 is top view thereof; and,

FIG. 7 is a bottom view thereof.

The even dashed broken lines in the embodiment of the fuse holder depict portions of the fuse holder that form no part of the claimed design. The dash-dot broken line represents the claim boundary and forms no part of the claimed design.

1 Claim, 4 Drawing Sheets
